PAPER CONTAINER LINING MACHINE

Robert S. Condon, Rutland, Vt., assignor to Continental Can Company, Inc., New York, N. Y., a corporation of New York

Application April 25, 1949, Serial No. 89,550

20 Claims. (Cl. 93—36.01)

1

The invention relates generally to the art of lining paper containers and primarily seeks to provide a simple and efficiently operable machine adapted for forming and shaping corrugated liners from a continuous strip of liner material and inserting the formed and shaped liners into serially presented paper containers.

Cup-like containers formed of paper to comprise a cylindiform body and a bottom or end closure and adapted to be covered by a closure of the slip-on or other type are well known and in widespread use in the packaging of confections, foodstuffs and the like. In the packaging of some products it is desirable that a liner be placed in each container before the products to be packaged are placed therein. In some instances these liners are formed of corrugated paper in order to provide a cushioning or marking element engageable with the packaged product. The formation and insertion of such liners, in whole or in part by hand, is a tedious, time consuming and relatively expensive operation, and heretofore no practical machine has been devised for mechanically forming, shaping and inserting such liners. It is a purpose of the present invention to provide a novel machine structure embodying means for feeding liner material from a supply roll, means for corrugating the liner material, means for cutting said material into proper liner lengths, means for serially presenting containers at a liner inserting station, means for shaping each corrugated liner length into a cylinder opposite a container at said station, and means for inserting each shaped liner into a container presented at said station.

Another object of the invention is to provide a machine of the character stated in which the means for corrugating the liner material also serves as means for drawing said material from the supply roll.

Another object of the invention is to provide a machine of the character stated in which the corrugating means comprises a pair of cooperating continuously rotating rolls.

Another object of the invention is to provide a machine of the character stated in which the continuously fed strip of liner material is corrugated as it is fed and is severed into corrugated liner lengths by an oscillating shear, in which each said liner length is wound into liner form about a rotary mandrel, in which containers to be lined are serially presented at and released from the lining station by an oscillating escapement means, and in which there is included a reciprocable pusher means for pushing each

2

wound liner into the container at that particular time presented at the lining station.

With the above and other objects in view that will hereinafter appear, the nature of the invention will be more clearly understood by reference to the following detailed description, the appended claims, and the several views illustrated in the accompanying drawings.

In the drawings:

10 Figure 1 is a vertical longitudinal sectional view illustrating the invention, the mandrel and the container feed being shown in elevation.

Figure 2 is a vertical cross section taken on the line 2—2 on Figure 1.

15 Figure 3 is an enlarged fragmentary longitudinal section illustrating a liner in the process of being pushed into a container.

Figure 4 is an enlarged fragmentary vertical cross section taken on the line 4—4 on Figure 3, 20 the cutting devices having just completed the cutting of a liner length.

Figure 5 is an enlarged fragmentary vertical cross section taken on the line 5—5 on Figure 3, the escapement being shown in position for holding a container in position to receive a liner in dotted lines and in position for releasing a lined container and supporting the following containers in full lines.

Figure 6 is an enlarged fragmentary vertical cross section taken on the line 6—6 on Figure 3.

25 Figure 7 is a vertical cross section taken on the line 7—7 on Figure 1.

Figure 8 is a vertical cross section taken on the line 8—8 on Figure 1.

Figure 9 is a horizontal section taken on the line 9—9 on Figure 1.

Figure 10 is a horizontal section taken on the line 10—10 on Figure 1.

Figure 11 is a fragmentary horizontal section taken on the line 11—11 on Figure 7.

Figure 12 is a diagrammatic view illustrating one manner of connecting the machine with a current supply, a safety switch being included in the circuit.

45 Figure 13 is a perspective view illustrating the invention.

Figure 14 is an enlarged fragmentary longitudinal section illustrating the yieldable end or pusher portion of one of the pusher bars, the same being shown as being displaced by contact with the liner during retraction of the respective bar.

Figure 15 is a diagram illustrating the timing of the machine operation, or in other words the timing relation of the strip cutting, strip wind-

ing or liner shaping, the liner placement, and the liner receiving can placement or escapement operation.

In the example of embodiment of the invention herein disclosed there is included a frame base portion including a pair of parallel longitudinal base beams 5 which are connected at one end as at 6, and at the other end by a transverse base beam 7. A channel beam 8 also connects across and above the longitudinal beams 5 near the base beam 7 and to it are secured parallel spaced frame uprights 9 and 10. An intermediate upright 11 is secured as at 12 to the upright 10 and extends upwardly in parallel spaced relation to the before-mentioned frame upright 9 in the manner clearly illustrated in Figure 1 of the drawings. The uprights 9 and 11 are held in rigid spaced relation near their upper extremities by a spacer beam or shelf 13 which is secured between them. An angle 14 secured to 10 said spacer beam serves as an upper anchor for a pair of parallel diagonal brace supports 15 which are anchored at their lower ends to the longitudinal base beams 5.

The diagonal base supports 15 form a trunnion 25 support as at 16 for a tape supply roll 17, an anti-friction support 18 preferably being provided as a part of said trunnion bearing.

If desired, spacer rods 19 may be provided as additional means for securing the desired spaced relation of the upper end extremities of the frame uprights 9 and 11.

A mandrel shaft 20 is provided and is rotatable in a bearing 21 provided therefor in the frame upright 9, and in a sleeve bearing 22 supported by the upright 11. A mandrel 23 is secured to one end of the shaft 20, and a hub extension 24 of this mandrel provides the bearing for the particular end of the shaft 20 within the before-mentioned bearing sleeve 22. It will be apparent by reference to Figures 1, 3 and 4 of the drawings that the mandrel 23 is radially and longitudinally slotted as at 25 to receive the longitudinally reciprocable liner discharging pusher bars 26, four of said bars being shown in this particular disclosure of the invention. The bars 26 are removably secured as at 27 to a sleeve 28 which is longitudinally slideable on the mandrel shaft 20. It will also be noted that the sleeve 28 is equipped with an annular groove 29, and the purpose of this groove will become apparent as the description progresses. It will also be noted by reference to Figures 3 and 4 of the drawings that the mandrel 23 is equipped with a plurality of rubber strip inserts 30 which project from the periphery of the mandrel intermediately of the positions of the pusher bar accommodating slots 25. The rotatable mandrel is surrounded by a cylindrical guide 31 which is supported as at 32 on the frame upright 11. It will be apparent by reference to Figure 4 that the guide extends entirely about the mandrel in spaced relation but for the limited width entrance at 33 which is defined at one side limit by a guide or stripper nose 34 and at the other by the bevelled deflector edge 35. At its outer end the guide is attached at 36 to a paper container chute frame wall 37 which will be described in greater detail hereinafter. Adjacent its other end extremity the mandrel shaft 20 has a sprocket 38 affixed thereto as a means through which rotation is imparted to the shaft in a manner to be described hereinafter.

A cam shaft 39 is provided and is rotatable in a bearing 40 in the frame upright 9 and a bear-

ing 41 in the frame upright 11. A barrel cam 42 is fixed on the shaft 39 and the peripheral cam groove 43 thereof receives a roller 44 which projects from one end of an actuator lever 45. The actuator lever 45 is pivoted intermediate its ends as at 46 on the shelf 13, and at its lower end is equipped with a roller 47 which engages in the groove 29 in the before-mentioned pusher bar shifter sleeve 28. Thus it will be apparent that upon rotation of the cam 42, the groove 43 thereon will be effective to rock the lever 45 and serve to project and retract the pusher bars 26 at the proper time.

The cam 42 also has a peripheral recess 48, and a cam finger 49 projects endwise therefrom. The purpose of these parts will be described hereinafter. There is a sprocket 50 affixed to the cam shaft 39, and this serves as a part of the means through which rotation is imparted to the shaft and the cam 42 thereon.

A corrugated roll 51 also is secured to the cam shaft 39, and this roll meshes with a cooperating idler corrugated roll 52 which is freely rotatable on a spindle 53 secured in a pair of arms 54 mounted on the shaft 39. Adjustable backing screws 56 are threaded into receiving bores in the arms 54 and these extend into longitudinal slots in the arms through which the ends of the spindle 53 extend and serve as positioning means for said spindle. A bracket 57 secured as at 58 to the frame upright 11 serves as a support for the free ends of the arms 54.

The liner material strip or tape 59 is drawn off the supply roll 17 over a roller 60 carried at the free end of a tensioner arm 61 which is pivoted at 62 on the frame upright 11. The arm 61 is yieldably lifted by an anchored spring 63 and is equipped with an intermediate roll 64 under which the tape 59 passes. After passing under the intermediate roll 64 the tape 59 or strip of lining material passes between the cooperating corrugating rolls 51 and 52 and through free guides 66 which are loosely mounted in and suspended from grooves in the rolls 51 and 52 as at 67.

A fixed cutter member 68 is secured as at 69 on the frame upright 11 and is equipped with a horizontally disposed cutter edge 70. The fixed cutter edge 70 is engageable by a movable cutter edge 71 carried by an oscillatable cutter 72 which is pivoted as at 73 between the lower ends of the actuator arms 74 which are secured at their upper ends to a rock shaft 75. The rock shaft 75 is rockably mounted in a bearing 76 on the frame upright 11 and in a bearing 77 on the frame upright 9. Anchored springs 78 constantly urge the pivoted cutter member 72 upwardly for engagement in shearing contact relation with the fixed cutter edge 70, and an overlapping guide lug 79 engageable with the fixed cutter member serves to maintain the proper shearing relation of the cutting edges in a manner assuring against overlapping and jamming of said edges. A crank arm 80 secured on the rock shaft 75 is equipped with a roller which engages with the periphery of the cam 42 in position for dropping into the cam recess 48 once during each full rotation of said cam. Another crank arm 82 is secured on the rock shaft 75 and is connected with anchored springs which constantly tend to force the roller 81 against the cam and into the cam recess 48. As the crank arm carried roller 81 drops into the recess 48 the springs 83 will impart inward swinging movement to the arms 74 and cause the movable cutting edge 71 to engage in shearing re-

lation with the stationary cutting edge 70 for cutting off a corrugated liner length, it being understood that as the strip or tape 59 is drawn downwardly through the corrugating rolls 51 and 52 it is corrugated thereby and passes downwardly between the pendant strip guides 66. Since the rolls 51 and 52 rotate continuously, there will be a limited amount of buckling up of the corrugated tape length between the guides 66 as the cooperating shearing edges 70 and 71 are cooperating in severing a liner length from said tape or strip.

An upper driven pulley shaft 84 is provided and is rotatably mounted in a bearing 85 in the frame upright 9 and in a bearing 86 in the frame upright 11. A pulley 87 is secured on the shaft 84 and is equipped with spaced, belt receiving grooves placed near the ends thereof. A cooperating lower idler pulley 88 of like construction is disposed just above the position of the mandrel in the manner clearly illustrated in Figure 4 and is rotatably mounted on a stud shaft 89 which is secured as at 90 on the frame upright 11. Relatively short belts 91 take over the upper driven pulley 87 and the lower idler pulley 88, being disposed in the grooves thereof so as to bear spaced parallel relation one with the other.

A lower driven pulley 92 constructed in like manner as are the previously mentioned pulleys is provided and disposed slightly above and to one side of the mandrel in the manner clearly illustrated in Figure 4. The pulley 92 is secured on a shaft 93 which is rotatably mounted in the bearing 94 provided therefor in the frame upright 9, and in the bearing 95 provided therefor in the frame upright 11. The lower driven pulley 92 cooperates with a similarly constructed upper idler pulley 96 which is mounted beside the previously described upper driven pulley 87 on a stud shaft 97 which is secured as at 98 on the frame upright 11. Relatively long belts 99 take over the upper idler pulley 96 and the lower driven pulley 92, being mounted in the grooves in said pulleys in position for opposing and cooperating with the previously described relatively short belts 91.

An electric motor 100 is suitably supported on the base framing and serves to drive the power out-put shaft 101 through a suitable speed reduction gearing generally designated 102. A driver sprocket 103 is secured on the driver shaft 101 and drives a chain 104 which serves to impart rotation to all of the rotating parts of the machine. The chain 104, as viewed in Figures 1 and 8 of the drawings, passes upwardly behind the lower driven pulley sprocket 105 on the shaft 93 for driving the lower driven pulley 92, thence over the cam shaft sprocket 59 for driving the cam shaft 39, the cam 42 and the corrugating rolls 51 and 52, thence downwardly behind the upper pulley shaft sprocket 106 on the shaft 84 for driving the upper driven pulley 87, thence downwardly in front of the tightener sprocket 107 which idles over the stud 108 adjustably mounted as at 109 on the frame upright 9, then behind the sprocket 38 on the shaft 20 to rotate the mandrel 23, and finally about the before mentioned driver sprocket 103.

The frame wall 37 forms a part of a paper container chute which is made up of said frame wall, two side walls 110 and 111 and a front wall 112. The front wall 112 preferably is hinged as at 113 so as to be swingable away in the manner indicated in Figure 12 so as to make the interior of the chute readily accessible. The paper con-

tainers which are to be lined are fed into the chute structure by any suitable conveyor means 114, and the lined cans are fed away from said chute structure by any suitable feed away conveyor means 115.

An escapement lever structure 116 is secured on the rock shaft 117 which is rockably mounted in the bearing 118 provided therefor in the frame upright 9, and in the bearing 119 provided therefor in the frame upright 11. An actuator lever 120 also is secured on the rock shaft 117 and projects upwardly therefrom into position for being engaged by the actuator pin 49 projecting from the end of the cam 42. The escapement lever 116 is equipped with an upper escapement pin 121 and a lower escapement pin 122, said pins projecting outwardly from said lever, or to the right as viewed in Figure 1, and being disposed to operate in and through slots 123 provided in the frame plate 37. It will be apparent that the escapement lever structure 116, 120 will be shifted once for each revolution of the cam 42. When the escapement pins are positioned as shown in Figure 2 of the drawings the pin 122 will cooperate with the side walls 110 and 111 of the chute structure in supporting the lowermost paper container in axial alignment with the mandrel 23, or in other words are positioned for receiving a corrugated liner pushed longitudinally from without the annular space between the exterior of said mandrel and the interior of the cylindrical guide 31. Obviously the remaining paper containers in the chute will be supported upon the lowermost container which rests upon the escapement pin 122. When the escapement lever is shifted to the left as viewed in Figure 2, the pin 122 will be displaced from its container supporting and aligning position and will free the lowermost, then lined container and permit it to fall into the feed away conveyor 115. This shifting of the escapement lever to release the lined container will bring about a moving of the upper escapement pin 121 to the left, or into position for intercepting and supporting the second and the overlying remaining containers in the chute, and after shifter pin 49 moves out of contact with the actuator lever 120 the escapement lever will be permitted to return to the position illustrated in Figure 2 in which the upper escapement pin 121 will be displaced and the lower escapement pin 122 will be returned into position for intercepting and supporting the containers in the chute structure with the lowermost container accurately aligned with the mandrel as aforesaid. It will be apparent by reference to Figures 2 and 13 of the drawings that the anchored spring 124 connected with the actuator lever 120 constantly tends to hold said lever in the position illustrated in Figure 2.

In Figure 12 of the drawings there is illustrated one simple manner of connecting the motor with a power source, a safety cut-out switch being included in this connection. In this illustration the motor circuit line 125 is connected with one power line 126 and has a switch 127 spliced therein through which the machine can be manually controlled. The circuit line 125 also connects with a safety switch 128 which is normally closed whenever the hinged chute structure door 112 is closed. For this purpose the switch 128 is of the normally open type and the hinged chute door 112 is equipped with a contact member 129 which engages the contact of the switch 128 and holds the same in the closed condition whenever the door 112 is in its normal

properly closed position. The switch 128 is connected through a circuit line 130 with the motor 100 which is in turn connected through the circuit line 131 with the power line 132. It will be apparent by reference to Figure 12 that whenever the hand switch 127 is closed and the chute structure 12 is closed the circuit through the motor 100 will be completed and the parts of the machine will be in operation. Whenever the hand switch 127 is opened, or the hinged chute door 112 is opened the circuit through the motor will be broken and the operation of the machine will be stopped.

It is to be understood that the strip of liner material 59 is as wide as the height of the can body intended to be lined thereby. As the strip is drawn downwardly between the corrugating rolls 51 and 52 it is corrugated thereby and fed downwardly between the guides 66. The parts are so timed that each time the crank arm carried roller 81 drops into the recess 48 a length of the liner material will have passed through the corrugating rolls 51 and 52 and below the shearing edges 70 and 71 sufficient to form a container liner and said shearing edges will come together to shear off this liner length. The severed liner length is conveyed downwardly by the cooperating belt sets 91 and 99 and is directed into the guide entrance 33 in the manner illustrated in Figure 4. The continuously rotating mandrel 23 and the rubber inserts 30 thereof cause the liner to be wound about the mandrel within the cylindrical guide 31, and as the formation of the liner cylinder is completed the cam groove 43 functions to shift the lever 45 and cause the pusher bars 26 to displace the shaped liner longitudinally in the manner illustrated in Figure 3 and insert the same into the container aligned opposite the mandrel by the escapement pin 122. The pusher bars 26 are then promptly retracted so that the next liner strip can be directed into the shaping guide and about the constantly rotating mandrel, and the escapement devices function in the manner previously described to release the lined container into the feed-away conveyor 115 and momentarily support the remainder of the supply of containers, and then to shift back to the position illustrated in Figure 2 to again support the lowermost container now aligned with the mandrel for receiving the next shaped and longitudinally displaced corrugated liner.

As before stated, the rotation of the mandrel, the cam 42, the corrugating rolls 51 and 52 and the driven pulleys 87 and 92 is continuous, and the machine functions to shape and insert the liners with great rapidity.

The particular manner of arranging and operating the parts as herein disclosed provides advantages in the way of simplicity in structure and accuracy and rapidity in operation. For example, the employment of the rolls 51 and 52 as both feeding and corrugating means serves not only to simplify the structure but also to provide for smooth and positive feeding of the strip. The knife 71 operates intermittently to cut proper liner lengths from the continuously fed strip, and the rolls 51 and 52 and the guides 66 are so arranged with relation to the cutting devices that the non-cut and feeding strip length above the cutting devices immediately after each liner length severance is permitted to crowd or bunch up above the momentarily engaged cutting edges 70 and 71. It will be apparent that the chain drives the feeder belts 91, 99 through the small 75

sprockets 106, 105 at a greater linear speed than the peripheral speed of the feeding and corrugating rolls 51, 52, and thus each severed liner length is rapidly fed away from the cutting edges 70, 71 and presented to the winding mandrel 23 within the guide 31 so that it can be shaped into a liner and properly ejected by the pusher bars 26 into a can positioned to receive the same. The speed of rotation of the corrugating and feeding rolls 51, 52 and the spacing of the cutting edges 70, 71 therebelow are so arranged as to provide just the right length of strip extension to be severed in the formation of a proper liner length.

In the diagram Figure 15 the space between the dot and dash lines A—A, B—B represents the 360° of circumference of the rotary cam 42 which serves to actuate the cutting edge 71, the liner inserting pusher bars 26 and the escapement lever 116, and the line 133 extending across between said dot and dash lines represents a development of the actuator groove 43 of said cam and the timing of the liner pusher bars 26. The line 134 represents a development of the escapement operation timing, the line 135 represents the timing of the strip feeding and winding, and the line 136 represents the timing of the strip cutting. By reference to this simple diagram it is possible quickly to determine the cooperative relation and timing of the several operating parts, the formation and insertion of the liners.

It will be apparent from the diagram in Figure 15 that the winding of each liner strip about the mandrel is commenced before the retraction of the pusher bars 26 is completed. This is made possible by providing each pusher bar 26 with a pivotally mounted pusher end portion 26a. Each said end portion is normally held in its projected or effective position shown in Figure 3 by a spring rod equipment 26b, but is free to yield in the manner indicated in Figure 14 when the bars are being retracted through a liner being wound about the mandrel and will again spring out behind said liner to the Figure 3 position as soon as it is fully retracted or clear of said liner.

More, specifically, in operation, the bars 26 on the injection stroke push the formed liner off the mandrel into the waiting can body. Just as the bars commence to retract, at a slower rate, the next corrugated strip reaches the mandrel and is gripped between the rubber inserts 30 and the guide wall 31. The retracting bars slide underneath the liner and the spring urged end portion 26a of each bar is depressed as it contacts the edge of the liner as shown in Figure 14 and stays depressed while passing under or along the corrugations until fully retracted, when the spring rod equipments 26b will serve to snap said bar end portions to their raised or projected position behind the liner. After a short dwell the bars 26 are again advanced to push the formed liner into the next waiting can body as shown in Figure 3.

While one form of the invention has been shown for purposes of illustration, it is to be clearly understood that various changes in the details of construction and arrangement of parts may be made without departing from the spirit and scope of the invention as defined in the appended claims.

I claim:

1. In a machine of the character described, means for directing a strip of liner material from a supply roll, means for corrugating the

strip of liner material, means for cutting said strip of corrugated liner material into proper liner lengths, means for serially presenting containers at a liner inserting station, means for shaping each corrugated liner length into a single walled cylindrical liner opposite a container at said station, and means for inserting each shaped liner into a container presented at said station.

2. In a machine of the character described, means presenting a continuous strip of liner material, means for cutting the strip into liner lengths, cooperating corrugating rolls for continuously feeding the strip to the cutting means and for corrugating the same as it is being fed, means for serially presenting containers at a liner inserting station, means for shaping each corrugated and cut liner length into a single walled cylindrical liner opposite a container at said station, and means for inserting each shaped liner into a container presented at said station.

3. In a machine of the character described, means for directing a strip of liner material from a supply roll, means for corrugating the strip of liner material, means for cutting said strip of corrugated liner material into proper liner lengths, means for serially presenting containers at a liner inserting station, guide means for confining each cut and corrugated length of liner material in the form of a single walled cylindrical liner opposite a container at said station, opposed belt means for presenting each cut and corrugated length of liner material to said guide means, and pusher means for pushing each cylindrical liner into a container presented at said station.

4. In a machine of the character described, means presenting a continuous strip of liner material, means for cutting the strip into liner lengths, cooperating corrugating rolls for continuously feeding the strip to the cutting means and for corrugating the same as it is being fed, means for serially presenting containers at a liner inserting station, guide means for confining each cut and corrugated length of single walled liner material in the form of a cylindrical liner opposite a container at said station, opposed belt means for receiving the liner lengths as they are cut and presenting them to said guide means, and pusher means for pushing each cylindrical liner into a container presented at said station.

5. A machine structure as defined in claim 1 in which the liner shaping means includes a rotary mandrel and the liner inserting means includes pusher devices rotatable with and slidably relative to the mandrel and engageable behind liners wound about the mandrel for pushing them off the mandrel and into containers aligned to receive them at the liner inserting station.

6. Machine structure as defined in claim 1 in which the liner shaping means includes a rotary mandrel and a guide member at least partially surrounding the same in spaced relation, in which there are included opposed belts for feeding the corrugated liner lengths from the cutting means to the guide means, and in which the inserting means comprises pusher devices engageable endwise with each liner in the space between said mandrel and guide and movable endwise with relation to the mandrel and the aligned container.

7. Machine structure as defined in claim 1 in which the shaping means includes a mandrel and the container presenting means includes a chute structure through which the containers gravitate in processional order and an oscillatable escape-

ment means having at least two alternately effective fingers one of which is effective to support a container in the bottom of the chute in alignment with the mandrel with the following containers resting thereon and the other of which is effective when said one is moved away to support said following containers as said bottom container is released and permitted to fall away by removal of said one finger.

10 8. Machine structure as defined in claim 1 in which the power for driving the several means is derived from an electric motor, in which the container presenting means includes a chute structure through which the containers pass and which includes a removable door through which access may be had to the interior of the chute, and in which the motor is served by a power circuit including a switch which is actuated by movement of the door so as to be closed whenever the chute door is properly closed and which is opened when said door is removed or improperly closed so as to open the circuit and discontinue operation of said motor.

9. In a machine of the character described, a continuously rotating mandrel, a guide surrounding the mandrel in spaced relation but for an entrance of limited width into said space, a pair of continuously driven cooperating corrugating rolls, means for directing a continuous strip of liner material between said rolls, shearing means for cutting the strip into liner lengths as it is fed between and corrugated by said rolls, opposed belts for directing the corrugated and cut liner lengths into the guide entrance to be wound into cylindrical form about the mandrel within the guide, means for serially placing containers in alignment with the mandrel and guide, and pusher means for pushing each shaped liner out of the guide and into a container presented in alignment therewith.

10. Machine structure as defined in claim 9 in which there is provided a single continuously rotating cam and means for actuating said shearing means and said pusher means from said cam in suitably timed relation.

11. Machine structure as defined in claim 9 in which there is provided a single continuously rotating cam and means for actuating said shearing means and said pusher means from said cam in suitably timed relation, and in which the mandrel, the rolls and the cam are driven through sprocket and chain connections with all sprockets engaged by a single driving chain.

12. Machine structure as defined in claim 9 in which the container placing means includes a chute structure through which the containers gravitate in processional order and an oscillatable escapement means having fingers alternately placeable for supporting all containers in the chute with the lowermost in alignment with the mandrel and guide or for releasing said lowermost container and supporting those following it, and in which there is provided a single continuously rotating cam and means for actuating said shearing means, said pusher means and said escapement means from said cam in suitably timed relation.

13. Machine structure as defined in claim 9 in which the container placing means includes a chute structure through which the containers gravitate in processional order and an oscillatable escapement means having fingers alternately placeable for supporting all containers in the chute with the lowermost in alignment with the mandrel and guide or for releasing said lower-

most container and supporting those following it, in which there is provided a single continuously rotating cam and means for actuating said shearing means, said pusher means and said escapement means from said cam in suitably timed relation, and in which the mandrel, the rolls and the cam are driven through sprocket and chain connections with all sprockets engaged by a single driving chain.

14. Machine structure as defined in claim 9 in which the container placing means includes a chute structure through which the containers gravitate in processional order and an oscillatable escapement means having fingers alternately placeable for supporting all containers in the chute with the lowermost in alignment with the mandrel and guide or for releasing said lowermost container and supporting those following it, and in which there is provided a single continuously rotating cam and means for actuating said shearing means, said pusher means and said escapement means from said cam in suitably timed relation, in which the power for driving the several means is derived from an electric motor, in which the container presenting means includes a chute structure through which the containers pass and which includes a removable door through which access may be had to the interior of the chute, and in which the motor is served by a power circuit including a switch which is closed whenever the chute door is properly closed and which is opened when said door is removed or improperly closed so as to open the circuit and discontinue operation of said motor.

15. In a machine of the character described, means for directing a strip of liner material from a supply roll, means for corrugating the strip of liner material, means for cutting said strip of corrugated liner material into proper liner lengths, means for serially presenting containers at a liner inserting station, means for shaping each corrugated liner length into a single walled cylindrical liner opposite a container at said station, means for feeding the cut liner lengths from the cutting means to the shaping means, and means for inserting each shaped liner into a container presented at said station, said liner length feeding means operating at an accelerated speed effective to provide spacing between successively cut liner lengths sufficient to allow each liner shaping and insertion to clear the succeeding presentation of a liner length to said shaping means.

16. In a machine of the character described, means presenting a continuous strip of liner material, means for cutting the strip into liner lengths, cooperating corrugating rolls for continuously feeding the strip to the cutting means and for corrugating the same as it is being fed, means for serially presenting containers at a liner inserting station, means for shaping each corrugated and cut liner length into a single walled cylindrical liner opposite a container at said station, means for feeding the cut liner lengths from the cutting means to the shaping means, and means for inserting each shaped liner into a container presented at said station, said liner length feeding means operating at an accelerated speed effective to provide spacing between successively cut liner lengths sufficient to allow each liner shaping and insertion to clear the succeeding presentation of a liner length to said shaping means.

17. In a machine of the character described, means presenting a continuous strip of liner ma-

terial, means for cutting the strip into liner lengths, cooperating corrugating rolls for continuously feeding the strip to the cutting means and for corrugating the same as it is being fed, means for serially presenting containers at a liner inserting station, guide means for confining each cut and corrugated length of liner material in the form of a cylindrical liner opposite a container at said station, opposed belt means for receiving the liner lengths as they are cut and presenting them at accelerated speed to said guide means to provide spacing between the liner lengths thus serially presented to said guide means, and pusher means for pushing each cylindrical liner into a container presented at said station.

18. In a machine of the character described, a continuously rotating mandrel, a guide surrounding the mandrel in spaced relation but for an entrance of limited width into said space, a pair of continuously driven cooperating corrugating rolls, means for directing a continuous strip of liner material between said rolls, shearing means for cutting the strip into liner lengths as it is fed between and corrugated by said rolls, opposed belts for directing the corrugated and cut liner lengths into the guide entrance to be wound into cylindrical form about the mandrel within the guide, said belts being driven at an accelerated speed with relation to said rolls so as to provide spacing between the liner lengths serially fed by the belts into said guide entrance, means for serially placing containers, in alignment with the mandrel and guide, and pusher means for pushing each shaped liner out of the guide and into a container presented in alignment therewith.

19. Apparatus as defined in claim 1 in which the means for shaping the liner lengths comprises a rotary mandrel about which said lengths are wound, and said inserting means comprises pusher bars longitudinally projectible and retractable with respect to said mandrel, there also being included means for operating the cutting means and the pusher means in timed relation so that before the pusher bars are fully retracted after being advanced to insert one liner another liner is being wound about said mandrel and the pusher bars, said pusher bars having spring projected pusher end portions normally tending to spring out into pushing position behind a liner but which are yieldable to permit retraction of the bars through a liner being wound on the mandrel.

20. In a machine of the character described, a continuously rotating mandrel, a guide surrounding the mandrel in spaced relation but for an entrance of limited width into said space, a pair of continuously driven cooperating corrugating rolls, means for directing a continuous strip of liner material between said rolls, shearing means for cutting the strip into liner lengths as it is fed between and corrugated by said rolls, opposed belts for directing the corrugated and cut liner lengths into the guide entrance to be wound into cylindrical form about the mandrel within the guide, said belts being driven at an accelerated speed with relation to said rolls so as to provide spacing between the liner lengths serially fed by the belts into said guide entrance, means for serially placing containers in alignment with the mandrel and guide, pusher bars longitudinally projectible and retractable with respect to said mandrel for pushing each shaped liner out of the guide and into a container presented in align-

ment therewith, and means for operating the shearing means, the belts and the pusher bars in timed relation so that before the pusher bars are fully retracted after being advanced to insert one liner another liner is being wound about said mandrel and the pusher bars, said pusher bars having spring projected pusher end portions normally tending to spring out into pushing position behind a liner but which are yieldable to permit retraction of the bars through a liner being wound on the mandrel.
